UNITED STATES PATENT OFFICE.

CHARLES F. EHRENTRAUT, OF PITTSBURGH, PENNSYLVANIA.

OUTAGE-GAGE.

1,275,409.

Specification of Letters Patent. Patented Aug. 13, 1918.

Application filed August 27, 1917. Serial No. 188,302.

To all whom it may concern:

Be it known that I, CHARLES F. EHRENTRAUT, a citizen of the United States, residing at Pittsburgh, in the county of Allegheny and State of Pennsylvania, have invented certain new and useful Improvements in Outage-Gages, of which the following is a specification.

My invention relates to improvements in means for indicating the level of the contents of a tank car or similar vessel, especially upon arriving at the shipping destination, whereby to avoid controversy as to the contents of the vessel when received by the consignee. It is particularly adapted to use in connection with tank cars or the like used in the shipment of volatile liquids as gasoline, naphtha, and the like.

Ordinarily, in connection with the shipment of such liquids in the usual cylindrical tank cars provided with the ordinary dome, there occurs more or less shrinkage due to evaporation, leakage, etc., known as "outage." Under certain circumstances, there is also at times an apparent accretion of liquid, due to expansion known as "domeage."

The invention comprises an indicating mechanism adapted to be located in the tank car, utilizing a float which assumes the level of the liquid when at rest at all times, and which is so arranged as to be positively fixed in position at the time that the cap of the dome is removed, when the contents are discharged. The float is freely mounted within a holding casing and provided with a pointer operable in connection with a registering scale, so that when the float is arrested at or before the time of discharge of the contents, it will accurately indicate the level of the liquid at the time of arrival of the car at its destination. The mechanism is so constructed as to be operable by the dome cap itself, upon unscrewing, and to be positively locked in position, when thus set, so as to effectually prevent accidental release of the float. It is also preferably protected by a coping or cover which prevents unauthorized tampering by the consignee.

One preferred embodiment of the invention is illustrated in the accompanying drawing in which:

Figure 1 is a vertical longitudinal sec-

tional view of a portion of a tank car showing the invention as utilized;

Fig. 2 is an enlarged sectional detail view showing the float within its casing, partly broken away;

Fig. 3 is a face view in elevation of the casing;

Fig. 4 is a plan view of the casing and the actuating mechanism for the float locking device;

Fig. 5 is a similar view illustrating the ineffective action of the lever in screwing on the dome cap;

Fig. 6 is a similar view showing the effective action in unscrewing the dome cap;

Fig. 7 is a plan view of the float and the arresting shaft; and

Fig. 8 is a view in elevation of the upper portion of the float casing and its parts at right angles to Fig. 2, from the other side shown in Fig. 3.

In the drawing, 2 represents the main body portion or tank of an ordinary tank car provided with the usual dome 3. 4 represents the level of the liquid therein as it may be after shipment, upon arriving at the point of destination, the space *a* indicating the "outage," *i. e.*, the shrinkage in the liquid below the top portion of the tank 2. "Domeage," *i. e.*, any increase above such level, is indicated by the line *b*. Variations in either respect are indicated by the rising and falling float 5 and the mechanism hereinafter described.

Said float, which may be of any buoyant material as cork, or of an air tight sheet metal construction, is preferably cylindrical in form and fits freely within the interior of the cylindrical casing 6. Said casing rests on its base upon the bottom of the tank car, as indicated at 7, and may be fixedly secured in place by any convenient means. The casing 6 is of sufficient length to extend into the interior of the dome 3 adjacent its top, and is located toward one side of the dome, as shown in Fig. 1, whereby to locate the actuating lever 8 of the mechanism within the path of a rotating pin 9 of cap 10. Said cap is ordinarily screwed into the central portion of the top 3' of dome 3, and pin or abutment 9 is located eccentrically of its center, as shown.

Float 5 is centrally apertured vertically throughout its length providing an opening

11 which is preferably segmental in cross section, as shown in Fig. 7, providing for a range of lateral movement of the locking pins 12 of a pin shaft or stem 13. Said stem is provided for partial rotation at the bottom and top of casing 6, and in the top 14 thereof as indicated at 15. Pins 12 extend laterally in alinement throughout the operative portion of the stem co-extensive 10 with the range of movement of float 5, and are adapted to be thrust around laterally and to engage, in the limited space between adjacent pins, an arresting plate 16 at one or both ends of the float. Ordinarily, the 15 pins extend in a non-registering direction with relation to plates 16, as shown in Fig. 7, so that float 5 is free to rise and fall within its casing, with the liquid contents of the tank car, except when stem 13 is thrust 20 around, as indicated in Fig. 6. In such case, the float is positively arrested, and its position in the casing is indicated by a pointer 17 with relation to a graduated gage 18, at one side of a longitudinal clearance slot *c*. 25 Stem 13 is provided with a lever arm 19 having a vertically adjustable locking pin 20, normally pressed downwardly by a spring 21, and pin 20 extends above the arm 19 providing a bearing for the end of lever 8. Pin 20 is adapted to ride over an inclined bearing 22 and to engage the abutment 23, or an equivalent socket, when the arm 19 is thrown around by lever 8, upon unscrewing cap 10. By this means teeth 12 engage plate 30 or plates 16, arresting the float, and the mechanism is so locked in position that it cannot be released without first pulling up the pin 20.

40 Lever 8 is maintained normally in its middle position by springs 24, 24, and is inoperative to affect lever 19 when the cap 10 is screwed on, because the inner end of lever 8 in such case moves away from the pin 20, resuming its normal central position each 45 time that pin 9 rides against and beyond it, until the cap is screwed on tight. The first contact of pin 9 with lever 8 in unscrewing, however, sets lever 19, rotating stem 13 and fixes the float, thus temporarily locating it 50 and indicating the level of the contents at the time of removal of the cap.

55 After record is made of the height of the contents in the tank, it may be emptied and lever arm 19 may be raised against the pressure of spring 21 and re-set in normal position for the next operation.

60 In order to prevent unauthorized tampering or readjustment of the mechanism by the consignee, or others than the shipper or seller, I cover the upper portion of casing 6 and the actuating mechanism with a coping or cap 25 having a movable top 26 and a lock 27. The coping is cut away, as at 28,

for clearance of lever 8. By this means it is impossible to first withdraw a portion of 65 the contents of the tank by hose or otherwise through the dome before emptying the tank in the usual way and to then reset the float to indicate the lowered level, as might be done when the pin 20 is accessible. 70

The advantages of the invention will be readily understood and appreciated by all those familiar with the custom of shipment of volatile liquids, and the uncertainties and difficulties of accurately determining or 75 agreeing upon the amount of loss or deterioration in shipment.

It automatically and positively registers the level of the liquid so that substantially exact computation may be made of any variation in transit, either in excess or diminution. 80

The device may be changed or varied in design, construction, or different details by the skilled mechanic, but all such changes 85 are within the scope of the following claims.

What I claim is:—

1. A level indicator consisting of a casing having a vertically and freely movable indicating float, a device for engaging, arresting and holding the float, and a lever adapted to engage and actuate said device. 90

2. A level indicator consisting of a casing having a vertically and freely movable indicating float, a device for engaging, arresting and holding the float, and a lever adapted to engage and actuate said device in one direction and to be ineffective in a reverse direction of movement. 95

3. A level indicator consisting of a vertically arranged slotted casing having a gage, 100 a buoyant float therein having a perforating opening and a locking cap, a rod extending through said opening and provided with a series of locking teeth, and means adapted to turn said rod. 105

4. A level indicator consisting of a vertically arranged slotted casing having a gage, a buoyant float therein having a perforating opening and a locking cap, a rod extending 110 through said opening and provided with a series of locking teeth, and a terminal lever, and a lever operable to actuate said terminal lever.

5. A level indicator consisting of a vertically arranged slotted casing having a gage, 115 a buoyant float therein having a perforating opening and a locking cap, a rod extending through said opening and provided with a series of locking teeth, a terminal lever having a spring-retracted locking pin, and a lever operable to engage said pin to actuate the terminal lever. 120

6. An outgate gage for tank cars consisting of a vertical casing provided with a buoyant float, a semi-rotatable stem extending 125 through the float and provided with a series

of projections adapted to engage and hold the float upon rotation, and lever mechanism extending across and operable by the cap of the dome of the tank car.

- 5 7. An outage gage for tank cars consisting of a vertical casing provided with a buoyant float having an indicator, a gage on the casing, a semi-rotatable stem extending through the float and provided with a
10 series of projections adapted to engage and hold the float upon rotation and a terminal lever, a spring-retracted pin on said lever, and a separate lever pivoted to the casing having one arm extending into range
15 of the lever pin and another arm extending across the cap of the tank car and into range of an abutment thereon.
8. In combination with a tank car having a dome and a rotatable cap therefor; a vertically arranged outage gage consisting of a slotted casing, a float therein having an indicating pointer, gage marks therefor, a vertical semi-rotatable stem having means for engaging and holding the float and a terminal lever, a separate lever pivoted to the casing and adapted to actuate said terminal lever and extending across underneath the dome cap, and an abutment on the dome cap adapted to engage said lever.

9. In an outage gage of the class described, in combination with a semi-rotatable arresting stem and its lever having a spring-retracted locking pin and a holding abutment for said pin, a lever operable in one direction to engage said pin and rotate the arresting stem and to be thrown away therefrom on opposite movement, a dome cap having an abutment operable to engage said lever in either direction, and equalizing springs for said lever. 30
35

10. A level indicator consisting of a casing having a vertically movable indicating float, a device for arresting and holding the float, a lever adapted to engage and actuate said device, and a movably mounted abutment adapted to engage said lever. 40
45

11. A level indicator consisting of a casing having a vertically movable indicating float, a device for arresting and holding the float, a lever adapted to engage and actuate said device in one direction and to be ineffective in a reverse direction, and a rotatably mounted abutment adapted to engage said lever in either direction of movement. 50
55

In testimony whereof I hereunto affix my signature.

CHARLES F. EHRENTRAUT.
